UNITED STATES PATENT OFFICE

CLIFFORD TRAUT, OF NEWPORT, KENTUCKY, ASSIGNOR TO THE HIGGIN MANUFACTURING COMPANY, OF NEWPORT, KENTUCKY, A CORPORATION OF WEST VIRGINIA

ROLLER SCREEN

Application filed March 5, 1929. Serial No. 344,470.

My invention relates to roller screens of the type which are set into a window with separate guide channels for the screen wire.

In those structures for the purpose of providing roller screens with which I am familiar, there is usually some provision for freedom of play of the side guides in which the screen end is mounted, or some play in the guide shoes on the end bar, which are held within the guides. This is the practice because of requirements that the screen retain its freedom of movement, in spite of inaccuracies of original structure, or inaccuracies arising because of changes arising after the screen has been installed.

One of the objects of my present invention is to provide a side guide structure and a type of guide shoe to be retained thereby, wherein the guide shoe has freedom of play in its engagement with the guide, and in which the shoe engagement is such that this does not result in making it possible to jam the screen by moving the end bar to a cocked position in the frame of the window.

Another object of my invention is to provide a type of guide shoe which will retain a considerable width of the wire of the screen, so that when the guide shoes are located in the side guides, there is a considerable portion of the wire, held within the guides by the shoes. The result of this arrangement is that the screen wire will be free to move in and out of the guides under wind pressure or accidental blows, but the limit of any expected movement of this type will never be enough to force the screen wire itself entirely out of the guides.

I accomplish my objects by that certain construction and arrangement of parts to be hereinafter more specifically pointed out and claimed.

In the drawings:—

Figure 1 is an elevation partly in section and centrally broken away showing a complete installation according to the preferred form of my invention.

Figure 2 is a view taken on the line 2—2 of Fig. 1.

Figure 3 is an end elevation of the roller box.

Figure 4 is a like view of the roller box turned on its side.

Figure 5 is a perspective of one of the guide shoes.

Figure 6 is a perspective of one form of bottom or end bar.

Figure 7 is a perspective of a side guide element.

I have indicated a window frame with side stiles 1, a sill 2, and a cap 3. Within a boarded space beneath the cap is secured a box for the rolling screen, which screen when unrolled and drawn down will cover the opening of the frame.

The box is formed of a piece of sheet metal formed into a hollow rectangular structure 4, with a lengthwise narrow opening 5, at its lower outer angle. In the lower wall of the box, close to the end and to the opening 5; ears 6 are cut out and turned down so as to be engaged by the side guides as will be noted.

The ends of the box are formed of flanged plates 7, with a central dished portion 7a, having a central hole or orifice 7b.

The ends of the rectangular structure are provided with tongues 9, which extend through slots 10 in the end plates, and in assembling the structure the end plates are set with their flanges over the ends of the box and with the tongues extending through the slots and turned over. (Figures 2 and 3).

The screen 11, is wound upon a roller 11a of cylindrical shape, having plates 12 near its ends, which have central holes to support a shaft 13. The shaft is slotted at one end as at 14, and squared at the other as at 15. A spring 16 is wound around the shaft and engaged in a disc 17, which slides along the shaft and has a notch therein to engage a lengthwise depression or channel in the roller. The spring is thus secured to the shaft and to a member which slidably engages the interior of the roller, so that by holding the shaft in position and revolving the roller, the spring will be compressed, as in any shade roller construction.

I provide, for supporting the shaft in one of the end pieces, a thimble 19, having spaced

flanges 20. The thimble has a square slot in it as at 21, to engage the squared end of the shaft.

In assembling the device, the roller, spring, 5 and shaft are assembled and set into the box, whereupon the end plates are set in place. The winding and latching thimble is thrust through the hole in the one end plate, so as to engage the squared end of the shaft and so 10 that its flanges lie in the dished portion of the end plate. The other end of the shaft, where it extends through the other end plate inserted through a thimble 19a welded into the end plate and the slotted end of the shaft 15 is fitted with a washer 22, (Fig. 6) which has integral tongues 23, that engage the slot of the shaft. The washer is brought down against the base of the tubular thimble and the tips of the shaft pinched together slightly, thus holding the shaft against withdrawal.

The end of the shaft which protrudes within the latching thimble is then engaged by a socket wrench and revolved so as to compress the spring. When this operation takes 25 place the flanges of the thimble will pass freely over the tongues of the end plate. When the spring has been tightened however, 30 the flanges of the thimble will catch under the tongues, thus locking the shaft against decompression movement.

The roller spring structure above described is shown and claimed in my copending application for Letters Patent Serial No. 35 315,694, filed October 29, 1928. An analogous roller shaft locking structure is shown in Letters Patent No. 1,766,746 issued June 24, 1930, to William F. Heckman.

In order to provide for side guides, and 40 to engage and move the screen across the window opening, I provide the screen itself with an end bar, and mount on the window frame guides which co-operate with shoes on the end bar.

45 The guides are formed of one or more pieces of metal having an attaching flange 24, and at right angles thereto spaced side walls 25, 25, with the ends of the walls turned in to form a pair of spaced guide walls 26, 26, 50 spaced from the side walls 25. In other forms the flange 24, may be an extension of one of the side walls, instead of at right angles.

The guides, one on each side of the window, 55 are screwed against the side stiles of the frame, so that presented at the upper ends of the guides are the flanges or plates 27, upon which the roller box rests. These plates extend across the space between the side walls 60 and the attaching flange, and have a slot 28 in them. The slots 28 receive lips 6 turned down from the forward corners of the box, thereby exactly locating the box with relation to the guides, so that the opening between the 65 guide walls of the guides registers with the

mouth of the box. The plates 27 may be integral or welded to the guides.

The bottom end of the screen is equipped with an end bar, which may be of any type. I have shown a structure formed out of sheet metal having a base flange 30, spaced side walls 31, and a central depressed portion 32, terminating in a tubular channel. The lower end of the screen, thickened with a wire or rod, can be fed into engagement with the bar by inserting the thickened end into the channel 32, and drawing the bar across the wire.

70 Into the open ends of the end bar, or secured in another desired way are the guide shoes. These are shown as having spaced 50 arms 33, for inserting into the guide bar, where they are secured fast in place, as with screws, or by welding. When made of one piece of metal the arms 33 are connected together at the bottom.

75 Extending from the arms are web portions 33a, which are close enough together to pass through the space between the guide walls of the side guide bars. The web portions are then turned back in the form of flanges 34, 80 such that the flanges will hook over and ride upon the inner faces of the guide walls of the side guides, as shown.

85 The upper edges of the guide shoes structure are open, and the screen wire is longer 95 than the end bar and extends out laterally, being held within the guide shoes. To the end of securing the wire in place in the guide shoes, ears 35, 35, are turned up, and screws or the like are passed through the ears and 100 through the wire. These ears are near enough to the outer edges of the shoes as not to interfere with the inner edges of the guide walls of the side guides.

105 Mounted within the shoes are bolts 36, which slide lengthwise, and are longer than the portion 33 of the shoes so that they extend into the end bar structure. They are equipped with finger pieces 37 which extend out through slots 38 in the end bar. The 110 tips of the latch bars are bevelled to an angular point, and lie in holes 38', which are formed in the edges of the portions 33 of the shoes, where they merge with the portions 33a.

115 When installing the screen, the workman with a file makes notches 39 at the proper places in the two side guides, and the latch bolts engage these notches. This is a very 120 practical way of avoiding any previous adjustment of the length of the side guides, and is possible because of the shape of the side guides, and the nature of the shoes.

125 With springs 40 urging the latch bolts outwardly (partially shown) the bolts will act as a brake to prevent too rapid movement of the screen in the guides.

130 It will be noted that the proportionate size of the several shoes and guide parts are such that the shoes when in place in the guides

will have some play, endwise of the end bar of the screen, and crosswise of the window frame.

However, due to the four surfaces of engagement between the parts, and the curved shape of the inner ends of the shoes, there is no danger of cocking the end bar of the machine during the operation of the screen and thus wedging it into a jammed position.

10 The play is not enough to permit the shoes to become jammed, and yet is enough to permit of sufficient lateral play to take up variations due to expansion and contraction, and errors which might be present in the window frame in which the screen is arranged.

15 A description of the operation of the screen will not be required. When the shoes are inserted in the guides, and the guides set into place, and connected by the end bar, the 20 screen will lie within the side guides, and when fully withdrawn from the box will entirely close the window.

25 Wind pressure will not force the screen out of the guides, since the structure is such that a considerable width of screen lies within the guides.

Having thus described my invention, what I claim as new and desire to secure by Letters Patent is:—

30 1. In a roller screen structure, having a screen and means for movably supporting said screen at one end of a window frame; an end bar and side guides in the frame in which the screen and end bar are engaged, 35 said guides having a lengthwise hollow portion and a lengthwise slot, with the walls defining said slot projecting inwardly into the hollow portion, members on said end bar which enter the slots of the guides, and have 40 tongues engaging the outer faces of the inwardly projecting slot defining walls.

2. In a roller screen structure, having a screen and means for movably supporting said screen at one end of a window frame; 45 an end bar and side guides in the frame in which the screen and end bar are engaged, said guides having a lengthwise hollow portion and a lengthwise slot, with the walls defining said slot projecting inwardly into the 50 hollow portion, members on said end bar which enter the slots of the guides, and have tongues engaging the outer faces of the inwardly projecting slot defining walls, said members having such substantial width 55 lengthwise of the guides as to be non-binding in their travel along the guides.

3. In a roller screen structure, having a screen and means for movably supporting said screen at one end of a window frame; 60 an end bar and side guides in the frame in which the screen and end bar are engaged, said guides having a lengthwise hollow portion and a lengthwise slot, with the walls defining said slot projecting inwardly into the 65 hollow portion, members on said end bar

which enter the slots of the guides, and have tongues engaging the outer faces of the inwardly projecting slot defining walls, said hollow portion of the guides, and end bar and members being so relatively proportioned 70 that the members have play transverse the lengthwise direction of the guides.

4. In a roller screen structure, having a screen and means for movably supporting said screen at one end of a window frame; 75 an end bar and side guides in the frame in which the screen and end bar are engaged, said guides having a lengthwise hollow portion and a lengthwise slot, with the walls defining said slot projecting inwardly into the hollow portion, members on said end bar which enter the slots of the guides, and have tongues engaging the outer faces of the inwardly projecting slot defining walls, said hollow portion of the guides, and end bar and members being so relatively proportioned 80 that the members have play transverse the lengthwise direction of the guides, the members on the end bar being rigidly associated therewith.

5. In a roller screen structure, having a screen and means for movably supporting said screen at one end of a window frame; 85 an end bar and side guides in the frame in which the screen and end bar are engaged, said guides having a lengthwise hollow portion and a lengthwise slot, with the walls defining said slot projecting inwardly into the hollow portion, members on said end bar which enter the slots of the guides, and have 90 tongues engaging the outer faces of the inwardly projecting slot defining walls, said hollow portion of the guides, and end bar and members being so relatively proportioned 95 that the members have play transverse the lengthwise direction of the guides, the members on the end bar being rigidly associated therewith.

6. A side guide and end bar arrangement for screens comprising in combination side guides having lengthwise openings defined by inwardly projecting walls, and an end bar having members which pass into the openings and engage the inwardly projecting walls, the members and guides being so relatively proportioned that the members have a freedom of motion between said walls, and their engagement with the inner walls of the 100 openings.

7. A side guide and end bar arrangement for screens comprising in combination side guides having lengthwise openings defined by inwardly projecting walls, and an end 105 bar, having members which pass into the openings and engage the inwardly projecting walls, the members and guides being so relatively proportioned that the members have a freedom of motion between said walls, 110

and their engagement with the inner walls of the openings, spring plungers in the end bar, said plungers serving as latches therefor, and arranged to engage the guides during the movement of the end bar.

8. In a window screen device including in combination with a wire fabric, an end bar with which said wire fabric is engaged, and shoes secured to the end bar, said shoes having spaced members between which the fabric is engaged, ears on said members between which the fabric is secured, and return-bent more widely spaced members serving to engage within suitable side guide members.
